UNITED STATES PATENT OFFICE.

JOHN ROGERS FLANNERY AND ETHAN I. DODDS, OF PITTSBURGH, PENNSYLVANIA,
ASSIGNORS TO FLANNERY BOLT COMPANY, OF PITTSBURGH, PENNSYLVANIA, A
CORPORATION OF DELAWARE.

STAY-BOLT STRUCTURE.

Application filed July 2, 1919. Serial No. 308,121.

To all whom it may concern:

Be it known that we, JOHN ROGERS FLANNERY and ETHAN I. DODDS, citizens of the United States, and residents of Pittsburgh, in the county of Allegheny and State of Pennsylvania, have invented certain new and useful Improvements in Stay-Bolt Structures; and we do hereby declare the following to be a full, clear, and exact description of the invention, such as will enable others skilled in the art to which it appertains to make and use the same.

This invention relates to improvements in staybolt structures, one object of the invention being to provide means whereby the bolt is connected with the outer boiler sheet in such manner that the mounting for the rounded head of the bolt shall be capable of universal movement to insure the proper and accurate alignment of the bolt between the two boiler sheets whether said sheets be parallel with or at an angle to each other, or the bolt opening in the inner sheet is not in exact alignment with the bolt opening of the outer boiler sheet, and to secure the inner end of the bolt to the inner boiler sheet in such manner as to effect a water and steam-tight connection and at the same time avoid upsetting of the inner end of the bolt and the danger of crystallization of the metal of the bolt, due to an upsetting operation.

With this and other objects in view, the invention consists in certain novel features of construction and combinations of parts as hereinafter set forth and pointed out in the claim.

In the accompanying drawings; Figure 1 is a sectional view showing an embodiment of our invention, and Figures 2 and 3 are views of modifications.

1 represents an outer boiler sheet and 2 an inner boiler sheet, the latter having a threaded opening 3 for the accommodation of the threaded inner end 4 of a staybolt 5. The staybolt is provided at its outer end with a rounded head 6 which may be partly spherical in form, and said bolt may be also provided with a tell-tale hole 7 extending from the inner end of said bolt to the headed end and terminating within the head 6, or the bolt may be made solid as shown in Figure 2.

The outer boiler-sheet is provided with

an opening which is larger at its outer than 55 at its inner end, and the wall of said opening may be made curved or concave transversely of the sheet to form a seat 8 for a bearing sleeve or bushing 9, as shown in Figure 1.

The sleeve or bushing 9 is made with a convex outer portion 10 where it engages the seat 8 in the boiler sheet, so that said sleeve or bushing shall be capable of universal movement when the bolt is being installed. The sleeve or bushing is provided internally with a curved or concave seat 10^a 65 for the rounded head of the staybolt. The portion 11 of the sleeve or bushing may be straight and threaded for the reception of 70 a cap or closure 12.

When the staybolt shall have been placed in position with the head mounted in the sleeve or bushing and the threaded inner end passing through the threaded opening 75 in the inner boiler sheet, (the sleeve or bushing moving automatically, if necessary, to effect proper alignment of the bolt relatively to its connections with the respective boiler sheets) the metal of said sleeve or 80 bushing may be permanently united to and made integral with the metal of the outer boiler sheet, by a weld indicated at 14.

The inner end of the staybolt is welded to the inner face of the inner boiler sheet 85 and in this manner the injurious effects of crystallization of the metal of the bolt which might occur were the end of the bolt subjected to an upsetting operation, will be obviated. Furthermore, the welding of the 90 inner end of the staybolt to the inner boiler sheet rather than upsetting said inner end of the bolt, is valuable when the headed outer end of the bolt is mounted in a bearing member which is capable of an initial 95 universal adjustment. After the parts have been properly adjusted, upsetting of the inner end of the bolt may interfere with such adjustment, but by securing the inner end of the bolt to the inner boiler sheet by 100 welding, there is no danger of throwing the bearing member out of adjustment prior to the welding of said member to the outer boiler sheet. In the construction shown in Figure 1, the inner end of the bolt projects 105 slightly beyond the inner face of the inner boiler sheet and a built-up weld 15 surrounding this projecting portion of the

bolt and overlying the inner end thereof, connects the bolt with the inner face of said inner boiler sheet, so that the end of the bolt and the boiler sheet will become an integral structure.

In Figure 3, the weld 15^a surrounds the threaded projecting portion of the bolt without overlying the inner end of the latter, while in Figure 2, the inner end of the 10 bolt is flush with the inner face of the inner boiler sheet, and the weld 15^b overlies both the end of the bolt and the inner face of the inner boiler sheet.

Having fully described our invention 15 what we claim as new and desire to secure by Letters Patent, is:—

In a staybolt structure, the combination with inner and outer boiler sheets having

openings, of a bearing member having initial universally movable mounting at the 20 opening in one boiler sheet, a staybolt having a head at one end movably mounted in said bearing member, said staybolt having its other end passing through the opening in the other boiler sheet, and means including a weld for uniting the last-mentioned end of the staybolt with the boiler sheet through which it passes.

In testimony whereof, we have signed this specification in the presence of two sub- 25 scribing witnesses.

JOHN ROGERS FLANNERY.

ETHAN L. DODDS.
